[57] CLAIM

The ornamental design for phlebotomy unit for blood sampling, as shown and described.

DESCRIPTION

FIG. 1 is a perspective view of a phlebotomy unit for blood sampling showing my new design;

FIG. 2 is a top plan view thereof;

FIG. 3 is a bottom plan view thereof;

FIG. 4 is a left side elevational view, the right side being the mirror image thereof;

FIG. 5 is a rear elevational view thereof; and,

FIG. 6 is a front elevational view thereof.

The broken line showing of the needle and tube in FIG. 1 is for illustrative purposes only and forms no part of the claimed design.

FIG. 4

FIG. 5

FIG. 6
